[57] CLAIM

The ornamental design for a bumper end for a truck, as shown and described.

DESCRIPTION

FIG. 1 is a perspective view of a bumper end for a truck showing our new design;

FIG. 2 is a front view thereof;

FIG. 3 is a right view thereof;

FIG. 4 is a back view thereof;

FIG. 5 is a left side view thereof;

FIG. 6 is a top view thereof;

FIG. 7 is a bottom view thereof;

FIG. 8 is a perspective view of a second embodiment of our invention;

FIG. 9 is a front view of FIG. 8;

FIG. 10 is a left view of FIG. 8;

FIG. 11 is a back view of FIG. 8;

FIG. 12 is a right side view of FIG. 8;

FIG. 13 is a top view of FIG. 8;

FIG. 14 is a bottom view of FIG. 8; and,

FIG. 15 is a reduced perspective view of the first and second embodiments showing the environment in which they can be used.

The broken line showing of a partial automobile, in FIG. 15, is for illustrative purposes only and forms no part of the claimed design.
